UNITED STATES PATENT OFFICE.

HARRY K. RUTHERFORD, OF PHILADELPHIA, PENNSYLVANIA.

FOUNTAIN BRUSH.

Application filed October 10, 1921. Serial No. 506,769.

To all whom it may concern:

Be it known that I, HARRY K. RUTHERFORD, a citizen of the United States, residing at Philadelphia, in the county of Philadelphia and State of Pennsylvania, have invented certain new and useful Improvements in Fountain Brushes, of which the following is a specification.

This invention relates to fountain brushes and provides a device of this type which includes in compact form a soap chamber, and a control valve which is conveniently operable to cause water to be fed to the brush either through or around such soap chamber.

The preferred embodiment of the invention is illustrated in the accompanying drawings, in which:—

Fig. 1 is a longitudinal axial section of the complete device.

Fig. 2 is an enlarged section on the line 2—2 of Fig. 1.

Fig. 3 is a view similar to Fig. 2 showing the valve in a different position.

Fig. 4 is a section on the line 4—4 of Fig. 3.

Fig. 5 is an elevation of the device with parts broken away to show the internal construction.

Fig. 6 is a perspective view, partly broken away, showing the spring plate of the valve and its sealing leather assembled.

Fig. 7 is a perspective view of the rotary valve.

Fig. 8 is a perspective view of the valve seat and its sealing leather assembled with each other, as they would appear before they are mounted in the cup-shaped fitting which houses the valve.

Fig. 9 is a fragmentary perspective view of the flanged end of the soap chamber.

Fig. 10 is a fragmentary axial section on an enlarged scale showing how the bristles are mounted on the brush shell.

Fig. 11 is a section on the line 11—11 of Fig. 10.

Fig. 12 is a fragmentary view similar to Fig. 1, showing a modification.

The valve structure is housed in, and the other parts of the device are removably mounted on a cup-shaped fitting 12 which has a tubular handle 13 to which a flexible hose 14 is connected. This hose brings water to the device from any suitable source. A heat-insulating grip 15 surrounds tubular handle 13 to protect the hand of the user

when the device is used with hot water. The handle 13 may have any angular relation to the brush, but I prefer the one illustrated in which the handle is at a slight angle to the longitudinal axis of the brush. 60

The valve structure includes a disc valve 16 rotatably mounted on a bolt 17 between a valve seat and a disc spring. The seat consists of a metal plate 18 which carries, riveted or otherwise suitably connected 65 thereto, a sealing gasket 19 of leather or the like. The spring consists of a dished plate of metal 20 also provided with a sealing gasket 21 of leather or the like. The bolt 17 not only serves as a journal for the 70 valve, but also offers means to apply pressure to spring disc 20 and thus produces sealing contact with both faces of the valve 16.

The plate 18 is fixedly mounted in fitting 75 12 by soldering or otherwise, the parts numbered 16 to 21 inclusive being assembled before the plate 18 is so mounted. The valve 16 is rotated by a finger piece 22 which projects through a slot 23 in fitting 12. 80 The finger piece 22 is bent to shape after the parts are assembled and is so positioned as readily to be manipulated with the thumb while the user grasps the grip 15. The spring plate 20 and its gasket 85 21 are held against rotation in casing 12 by means of a small lug 24 on the periphery of plate 20 which engages a shallow groove in fitting 12.

This maintains alinement of the ports in 90 the valve seat and spring member. There are two series of such ports in each member, an outer annular series of ports 25 and an inner annular series of ports 26. The valve 16 has an outer annular series of ports 95 27 and an inner annular series of ports 28. The ports 25, 26, 27 and 28, and the slot 23 are so dimensioned that in one limiting position of finger-piece 22 ports 25 are open and ports 26 closed, in the other limiting position ports 26 are open and ports 25 closed, and in an intermediate position all ports are closed.

The plate 18 carries two headed studs 29 which engage in key-hole slots 30 in flange 31 of the perforated cylindrical soap chamber or cage 32 and thus serve as means for releasably connecting chamber 32 to plate 18. Flange 31 has openings 33 which register with ports 25 of plate 18. 110

The ports are so located that ports 26 communicate with the interior of chamber 32 and ports 25 with the space surrounding said chamber, but within a second surrounding perforated shell 34. The shell 34 is threaded at 35 into fitting 12 and bears at its end against flange 31. The shell 34 thus holds flange 31 tightly against plate 18, the studs 29 being merely for convenience in assembling the device, and to maintain the alinement of openings 33 with ports 25.

The shell 34 not only holds cage or chamber 32 in place but also acts to sustain the relatively light shell 36 of the brush. The shell 36 is cylindrical and of metal spirally corrugated, so as to offer an external groove within which the bristles 37 are held by a wire 38 wound around the shell 36. The end of shell 36 also carries bristles 39 which are drawn through holes in the end plates and wired in place with wires 40. The sides and ends of shell 36 are perforated to permit the passage of water to the bristles.

Shell 36 fits loosely over shell 34 but fits tightly over the margin of fitting 12 to which it is held by pins 41 engaging in bayonet slots 42.

Since the shell 34 merely sustains shell 36, and acts as a locking ring to hold flange 31, it obviously is capable of considerable modification of form, according to the amount of support required by shell 36. The construction shown is adopted because simple and inexpensive.

In Fig. 12 I show a modification in which the shell 34 and the threads 35 as well as pins 29 and slots 30 of Figs. 1 to 11 are entirely omitted. The shell 36 is soldered at 43 to the flange 31 of shell 32, and the two shells thus form a unit structure which is releasably held in fitting 12 by the pins 41. In this case the pins 41 are preferably fixed in shell 36 and engage bayonet slots 42 in fitting 12. The pins 41 are preferably equal in number with ports 25 and uniformly spaced to ensure register of ports 33 and 25 while permitting the shell 36 to be mounted on fitting 12 in various positions.

In either construction the shell 32 may be perforated over its entire surface, as shown, or the perforations may be located chiefly at or near the end remote from valve 16. By locating the perforations at or near the end, the soap chamber and the surrounding space are more effectively isolated when ports 26 are closed and the water has a longer travel through the soap when ports 26 are open.

To prepare the embodiment of the device shown in Figs. 1 to 11 for use, the shells 36, 34 and 32 are successively removed, the shell 32 is partly filled with soap in pieces of moderate size and the shells are then replaced in reverse order. When the hose 14 is connected to a suitable water supply the valve 16 may be manipulated to cause clear

water or soapy water alternatively to flow to the brush. The valve serves also to cut off all water flow when desired.

Stated more specifically, in one limiting position of valve 16 water flows through handle 13 and ports 25 and 27 to the space between shells 32 and 34 and thence through shells 34 and 36 to the brush. In the other limiting position of valve 16 water flows through handle 13 and ports 26 and 28 to the interior of shell 32 where it dissolves and carries with it some of the soap contained in shell 32. Thence this soapy water flows through shells 32, 34 and 36 to the brush. In an intermediate position of valve 16 all water flow is cut off.

The embodiment shown in Fig. 12 operates in a similar manner.

Advantages offered by the invention are the simplicity and adjustability of the valve, the readiness with which the various shells may be removed and replaced, and the possibility of mounting the brush in different positions so as to equalize the wear, this last feature being secured by the symmetrical arrangement of a plurality of pins 41 and bayonet slots 42. Since the brush houses the water and soap chambers the structure is compact and contact of metal parts with objects being washed is prevented. The entire device including the valve, can be manipulated with one hand.

Certain substitutions and modifications are within the scope of the invention. For example, other scrubbing means, pervious to water, may be substituted for the bristle brush shown. As these are known equivalents in the art I deem it unnecessary to illustrate them. Hence I use the terms brush and brush head in the claims as a generic term to include such known equivalents, except where the term is specifically limited to bristles.

What I claim is:—

1. In a fountain brush the combination of a supporting member provided with a handle and a water connection; a hollow substantially cylindrical fountain brush head removably mounted on said supporting member with its axis extending in the general direction of the handle; a foraminous soap chamber mounted on said supporting member within and in spaced relation to said brush head; a multiple-way valve mounted on said supporting member constructed and arranged to direct water from said connection alternatively to the interior of said chamber or to the space between said chamber and said brush head; and an actuator for said valve mounted on said supporting member in position to be actuated by the hand of a user while grasping said handle.
2. In a fountain brush, the combination of a supporting member provided with a handle and a water connection; a hollow substan-

- 5 tially cylindrical fountain brush head removably mounted on said supporting member; a ported soap confining chamber removably mounted on said supporting member within and in spaced relation to said brush head; a multiple-way valve constructed and arranged to direct water from said connection alternatively to the interior of said shell and to the space between said shell
10 and brush head; and a swinging actuator for said valve mounted adjacent one end of said handle.
3. The combination of two perforate shells, one being removably mounted within
15 and in spaced relation to the other and adapted to contain soap; a brush structure pervious to water, said brush structure surrounding the outer of said shells and being sustained thereby; and a two-way valve
20 adapted to deliver water to the brush alternatively through said inner shell or through the space intervening between said shells.
4. The combination of a fitting having a
25 water connection; a hollow brush head removably mounted thereon, said head includ-
- ing a hollow shell of foraminous material serving as a base for the brush structure; a hollow foraminous shell smaller than the shell of said brush and releasably mounted within the same on said fitting; and a manually operable two-way valve in said fitting serving to admit water alternatively to the interior of said smaller shell and to the space intervening between said shells. 30
5. The combination of a fitting having a water connection; a rotary disc valve in said fitting having two concentric annular series of ports, the two series opening in alternation; two foraminous shells one mounted within the other; means for releasably holding said shells in such coactive relation with said valve, that one series of ports serves to admit water to the inner shell and the other series of ports serves to admit water to the space between said shells; and a removable 35 hollow fountain brush head surrounding said outer shell. 40
- 45 In testimony whereof I have signed my name to this specification.

HARRY K. RUTHERFORD.
